UNITED STATES PATENT OFFICE

2,460,517

CURTAIN FIXTURE

Ida Lundstrom, St. Louis, Mo.

Application March 29, 1945, Serial No. 585,552

6 Claims. (Cl. 211—105.2)

1

This invention relates to curtain fixtures.

The object of my present invention is to provide a curtain fixture embodying sectional curtain-rod members and supporting brackets therefor.

A further object of the invention is the provision of a curtain fixture, wherein the sectional curtain-rod members can be quickly mounted upon the supporting brackets, held against horizontal displacement relative to the brackets, and quickly demounted from the supporting brackets by lifting the mounting ends of the rod members therefrom.

A further object of the invention is to provide a curtain fixture wherein the mounting end of each sectional curtain-rod member can be moved vertically into and out of mounting position on the supporting brackets of the fixture, and, in which the front and back faces of the mounting ends, or sections of the curtain-rod have sliding engagement with upright staggered members fashioned on the supporting brackets.

A still further object of the invention is to provide a curtain fixture wherein the curtain-rod per se is longitudinally adjustable to fit windows, or doors of different widths.

A still further object of the invention is to provide a curtain-rod supporting bracket having three upright staggered plate sections with two of the sections thereof offset to protrude from an adjacent surface and the third, or intermediate plate section to provide curtain-rod mounting section receiving spaces therebetween.

With the above and other objects in view, the invention consists in the novel features of construction, arrangement and combination of parts hereinafter more fully described, and finally pointed out in the claims hereto appended.

Referring to the drawings:

Fig. 1 is a perspective view of one end of a sectional curtain-rod member embodying my invention.

Fig. 2 is a top plan view of the curtain-rod supporting bracket.

Fig. 3 is a front elevation of the bracket.

Fig. 4 is a side elevation of the bracket.

Referring now, in particular, to the supporting bracket A which can be formed from either sheet metal stock, or from plastic material, comprises a lower flat plate section 1 having a flat upwardly projecting finger 2 lying in a plane with the lower plate section 1, and a pair of flat upwardly projecting offset, or protruding fingers 3 disposed to either side of the finger 2 and to lie in a plane with each other providing thereby shoulders 4

2

at the juncture of the fingers 3 with the lower plate section 1, and, also providing a space D between the inner side edges 5 of the spaced fingers 3, which space D is disposed directly in front of and spaced from the finger 2, as clearly shown in Fig. 3. The lower plate section 1 and the finger 2 are provided with suitable openings 6 through which suitable fastening devices, such, for instance, as screws, or the like 7 can pass for securing the bracket to a window frame 8, a door, or the like.

The spaced upright flat fingers 2 and 3 are arranged in staggered relation, in plan view, as clearly shown in Fig. 2 so as to provide a space 15 E between the inner faces of the fingers 2 and 3, as shown in Fig. 4, to receive the mounting end of the sectional curtain-rod member B.

The curtain-rod per se, as illustrated in Fig. 1, is fashioned to be quickly mounted upon and 20 quickly demounted from the supporting brackets A heretofore described.

The sectional curtain-rod members B can be formed from sheet metal, or from plastic material, and when made from plastic material they 25 are very light in weight, and they can be in any pleasing and attractive color.

Each sectional curtain-rod member B has its outer end projecting rearwardly, as at 11, a suitable distance and then terminates in a relatively 30 short inwardly projecting mounting end 12 which lies substantially parallel with the front or long portion of the curtain-rod member B. This structure provides a return bend at the outer end of the sectional curtain-rod member B.

35 The mounting end 12 of each curtain-rod member B is designed to be quickly and vertically mounted and demounted from the supporting bracket A. The mounting end 12 can be of various designs or modifications to accommodate 40 a single design of supporting bracket A.

As shown in Fig. 1, the mounting end 12 of the rod member B is provided with a rearwardly projecting T-shaped offset mounting member, designated generally as F, and the offset member has 45 a flange 18 and a cross-head or mounting member 19. The mounting member 19 projects upwardly from the flange 18, lies parallel with the mounting end 12 and is rearwardly spaced therefrom. The flange 18 projects rearwardly from the juncture thereof with the material of the mounting end 12 of the rod member B so that the lower edges 20 of the cross-head or mounting member 19 50 will rest upon the shoulders 4 at the juncture of the fingers 3 on the plate 1 in the space E between upright fingers 2 and 3, and the flange 18 will lie 55

in the space D with its side edges in contact with the side edges 5 of the offset upright fingers 3 on the plate 1 of the bracket A, thus preventing horizontal displacement of the mounting end 12 of the rod member B relative to the bracket A.

From the foregoing description, it will be apparent that I provide a curtain fixture that is simple and comparatively inexpensive in construction, easily and quickly mounted upon and demounted from the supporting brackets and held thereon against sidewise movement relative to the brackets when mounted thereon.

The many advantages of the herein described invention will readily suggest themselves to those skilled in the art to which the invention relates.

It will be further obvious to those skilled in the art that various changes may be made in this device without departing from the spirit of the invention and therefore I do not limit myself to what is shown in the drawing, or described in the specification, but only as indicated by the appended claims.

What I claim is:

1. A curtain fixture comprising a bracket and a sectional curtain-rod, said bracket embodying a plate formed to provide three upright finger like members spaced in staggered relation with the two outer finger members being offset from the plate to form shoulder portions at the lower ends thereof to lie in advance of the plate and the intermediate finger member, said sectional curtain-rod embodying a curtain hanger section having a return bend at its outer end providing thereby a mounting end, a T-shaped mounting member projecting rearwardly and upwardly from the mounting end for a sliding fit between the two outer finger members of the bracket and adapted to rest upon the shoulder portions of the two outer finger members.

2. A curtain-rod having return bends at the ends thereof and mounting members on the return bends each comprising a portion bent rearwardly from the return bend, and a portion projecting upwardly from said rearwardly bent portion and projecting beyond the side edges thereof.

3. A curtain fixture comprising, in combination, a supporting bracket having spaced supporting hooks struck from a single plate providing

thereby spaced shoulders and an intermediate arm to the rear of the gap formed by the spaced hooks, a curtain-rod having supporting ends in the form of return bends, means formed from the return bend material providing a rearwardly bent portion adapted to lie in the gap between the two hooks and an upright portion projecting from the rearwardly bent portion, and said upright portion projecting beyond the opposed side edges of the rearwardly bent portion and adapted to rest on the shoulders of the two spaced hooks.

4. In combination, a supporting bracket having a pair of fingers offset from the bracket and horizontally spaced forming thereby spaced shoulders at the lower ends of the fingers, and a sectional curtain-rod member having a return bend at one end thereof providing thereby a mounting end, and a T-shaped mounting member rearwardly offset from the mounting end adapted to rest at the end portions upon the aforesaid spaced shoulders.

5. A sectional curtain-rod comprising a curtain hanging section having a return bend at the outer end thereof, a flange integral with and projecting rearwardly from the return bend, and a mounting member projecting upwardly from the rear edge of the flange.

6. A sectional curtain-rod member as defined in claim 5, wherein the mounting member lies parallel with the return bend and has greater width than the flange.
